INDICATING ELECTRIC LAMP

George E. Bidwell, Washington, D. C.

Application February 5, 1937, Serial No. 124,346

5 Claims. (Cl. 240—1)

My invention relates generally to electric lamps in which some means is provided to indicate at a distance that the lamp is alight, and particularly to an electric lamp arrangement of 5 this character wherein the light emanating from the lamp itself is conveyed to the distant point to indicate to an observer at that point that the lamp is in operation, and an important object of my invention is to provide an indicating lamp arrangement of the character indicated which is 10 simple and inexpensive and is easy to install and operate.

Another important object of my invention is to provide an indicating lamp arrangement of 15 the character indicated above which eliminates the necessity for incorporating a tell-tale lamp in series with the lamp energizing circuit, with the attendant expense and difficulty of installation and operation.

20 Another important object of my invention is to provide in an indicating lamp arrangement of the character indicated above, means for conveying intelligence of the operation of the lamp to an observer at a distant point, which eliminates the necessity and desirability of a tell-tale 25 lamp in circuit with the main lamp, and the frequent replacement of the tell-tale lamp which is necessitated by its smaller capacity than the main lamp and its subjection to the same current as the main lamp; or the provision of relay 30 means to temper the energizing current to the smaller tell-tale lamp.

Another important object of my invention is 35 to provide an indicating lamp structure of the character indicated which is especially adapted for use in closets and the like, in the use of which persons commonly forget to extinguish the lamp and close the door thereof, and inadvertently leave the lamp burning; so that such person is 40 positively warned by indication at the outside of the closet that the bulb within the closet is still burning.

Another important object of my invention is 45 to provide an indicating lamp structure of the character indicated immediately above, in which the main lamp may be switched "on" or "off" from either the inside of the closet or the outside thereof.

Other important objects of my invention will 50 be apparent from a reading of the following description taken in connection with the drawings, wherein for purposes of illustration I have shown preferred embodiments of my invention.

In the drawings:

55 Figure 1 is a general elevational view of the

outside of the wall of the closet or the like in which the lamp structure is mounted, and showing the indicating lens.

Figure 2 is an elevational view of the inner side of the said wall showing the main lamp 5 structure.

Figure 3 is a vertical transverse sectional view taken through Figure 2.

Figure 4 is a longitudinal sectional view taken through the lamp structure and showing one 10 form of mounting of the light conveying tube.

Figure 5 is a view similar to Figure 4 of another embodiment of the invention involving a different manner of mounting the light conveying tube of the outlet box. 15

Figure 6 is a modified form of the invention in front elevation illustrating novel means for adjusting the lamp socket for any desired size of bulb.

Figure 7 is a side elevational view thereof 20 partly in section.

Figure 8 is a fragmentary rear elevational view of the plate.

Figure 9 is a side elevational view partly in section showing the position of the socket with 25 respect to the plate for a large size globe.

Figure 10 is a fragmentary vertical sectional view illustrating the manner in which the laterally extending arm of the socket is secured in adjustable position in the longitudinally extending 30 slot in the plate.

Referring in detail to the drawings, the numeral 5 generally designates the wall in which the lamp structure is mounted, this wall being either the door of the closet or other enclosure, 35 or one of the front or side walls thereof which is exposed within the room into which the closet opens. This wall has therein a horizontal opening 6 which opens at its inner end in a recess

7 which is of a size and form to receive a conventional outlet box 8 which is mounted therein as shown in Figure 3. The light conveying tube 9 lies within and along the passage 6 and has at 40 its outer end a housing 10 of suitable form which has a rim 11 which retains a jewelled lens 12 of 45 suitable indicating color such as red. The housing 10 has prongs 13 which engage the outer side of the tube 9 and the axially inward side of a retaining nut 13 which is threaded on the end of the tube 9 to hold the housing in place on the 50 tube 9 and in the recess 14 which is provided at the outer end of the passage 6 as shown in Figure 3. The lens 12 is spaced from the end of the tube 9 to pass the switch operating chain 15 which depends through an opening 16 provided 55

in the bottom of the housing 10 as shown in Figure 5.

The opposite or inner end of the tube 9 is threaded as indicated by the numeral 17 into one end of a bushing 18 into whose opposite end is threaded as indicated by the numeral 19 the auxiliary tube 20. The bushing 18 passes through a receiving opening in the wall 21 of the outlet box 8, and nuts 22 and 23 are threaded on the bushing 18 against opposite sides of the wall 21 of the outlet box to hold the tubes 9 and 20 properly connected thereto. The tube 20 has on its inner end the nut 24 which acts as a retainer for the wall plate 25 of the main lamp fixture and holds the wall plate 25 in engagement with the inner surface of the wall 5 so as to hold the main lamp 26 in place. The main lamp involves a bulb 27 mounted in a suitable socket 28 in which is a pull-pull switch 29 operated by a chain 30 which depends through an opening 35 in the bracket 32 which supports the socket 28 on the wall plate 25. The chain 15 is connected to the chain 30 and the chain 15 passes through the tubes 20 and 9 to and through the housing 10 as already explained. The main lamp energizing wires 31 come out of the outlet box 8 and pass through accommodating openings in the plate 25 and enter the socket 28 as illustrated in the drawings. It will be obvious in view of the described arrangement of the chains 15 and 30 that the main lamp 27 may be switched "on" and switched "off" by operation of either chain, from either the inner side of the wall 5 or the outer side thereof.

35 The axes of the tubes 9 and 20 are coincident or substantially so, and located so as to receive the light directly from the bulb 27, so that this light travels in a straight line or the equivalent to the jewelled lens 12 while the lamp 27 is alight, so that a person at the outer side of the wall 5 will be instantly and unmistakably informed that the bulb 27 is alight, whether or not he can see the bulb 27, as when the door of the closet is fully or partially closed.

45 A modified arrangement for connecting the tubes 9 and 20 with the outlet box 8 is illustrated in Figure 4 of the drawings, wherein the outlet box is generally designated 8' and the inner wall thereof 21'. In this instance the tube 9' is threaded in an accommodating opening in the wall 21' and into a sleeve 33 into whose opposite end the inner tube 20 is threaded, at the inner side of the wall 21'. At the outer side of the wall 21' a nut 34 is threaded on the tube 9' and 55 against the wall 21' to lock the connection.

Obviously, if so desired the inner surface of the light indicating device may be coated with a paint or any other non-light absorbing material to increase the efficiency of the terminal of the illuminating rays from the source of light to 60 the jewelled lens.

Referring now to Figures 6 to 10, inclusive, there is shown a further modified form of the invention in which, the plate 40 is provided with a centrally disposed longitudinally extending slot 42 in which there is adjustable by means of the nut 44 the laterally extending arm 46 carrying the lamp socket 48. It will be noted in this connection, that for proper illumination in closets 70 of different sizes, it is necessary to provide different sized bulbs and to this end, the arm 46 is longitudinally adjustable in the longitudinally extending slot 42 so that, the upper portion of the globe 50 regardless of the size thereof may be disposed directly opposite the tubing 52. For ex-

ample, as shown in Figure 7, the laterally extending arm is positioned in the slot 42 through the medium of the nut 44 for a globe of relatively small size and as illustrated in Figure 9 the laterally extending arm is positioned somewhat lower in the slot to accommodate a larger globe 56 to the end, that the upper portion of the globe 56 is disposed substantially adjacent the tubing 52 providing for an efficient communication of the light from the bulb 56 through the tubing 52. In the same manner as previously described with respect to Figures 1 to 3, inclusive, the socket 48 is provided with a depending pull chain 58 and a pull chain 60 extending upwardly and through the tubing 52 for access on the 15 outside of the closet.

Although I have shown and described herein preferred embodiments of my invention, it is to be definitely understood that I do not desire to limit the application of the invention thereto, and any change or changes may be made in the materials and in the structure and arrangement of the parts, within the spirit of the invention and the scope of the subjoined claims.

What is claimed is:

1. The combination with an electric lamp of a light conveying tube aligned therewith and extending away from the electric lamp, a light transmitting member at the end of the tube remote from said lamp, said lamp comprising a bulb, a socket receiving the bulb, a wall plate mounting said socket, an outlet box, means supporting said wall plate on said outlet box, said wall plate being provided with a longitudinally extending slot in which the socket is longitudinally adjustable at right angles with respect to the tube for accommodating lamps of different sizes.

2. The combination with an electric lamp of a light conveying tube aligned therewith and extending away from the electric lamp, a light transmitting member at the end of the tube remote from said lamp, said lamp comprising a bulb, a socket receiving the bulb, a wall plate mounting said socket, said wall plate being provided with a longitudinally extending slot in which the socket is longitudinally adjustable at right angles with respect to the tube for accommodating lamps of different sizes, and means extending through said tube for controlling the energization of said bulb.

3. The combination with an electric lamp of a light conveying tube aligned therewith and extending away from the electric lamp, a light transmitting member at the end of the tube remote from said lamp, said lamp comprising a bulb, a socket receiving the bulb, a switch to cut the lamp on and off, a wall plate mounting said socket, said wall plate being provided with a longitudinally extending slot in which the socket is longitudinally adjustable at right angles with respect to the tube for accommodating lamps of different sizes, said switch comprising an operative member having an actuating element extending through said tube for operation adjacent said light transmitting member, and a second actuating element for operation adjacent said lamp.

4. The combination with an electric lamp of a light conveying tube aligned therewith and extending away from the electric lamp, a light transmitting member at the end of the tube remote from said lamp, said lamp comprising a bulb, a socket receiving the bulb, a wall plate mounting said socket, an outlet box, means supporting the wall plate on said outlet box, said wall plate be-

ing provided with a longitudinally extending slot in which the socket is longitudinally adjustable at right angles with respect to the tube for accommodating lamps of different sizes, said socket being provided with a switch to cut the lamp on and off, said switch comprising an operative member having an actuating element extending through said tube for operation adjacent the end of the tube remote from the lamp, and a second actuating element for operation adjacent said lamp.

5. The combination with an electric lamp of an outlet box, of a pair of separably connected light transmitting tubes extending through said outlet box and being secured thereto, said tube having

one end disposed adjacent said electric lamp, said lamp comprising a bulb, a socket receiving the bulb, a wall plate mounting said socket, said wall plate being provided with a longitudinally extending slot in which the socket is longitudinally adjustable at right angles with respect to the tube for accommodating lamps of different sizes, said socket comprising a switch to cut the lamp on and off, said switch comprising an operative member having an actuating element extending through said tube for operation at a point remote from the end of the tube adjacent the lamp, and a second actuating element for operation adjacent said lamp.

GEORGE E. BIDWELL. 15
